ATTORNEYS

UNITED STATES PATENT OFFICE.

PHILIP KENNEDY, OF GLOVERSVILLE, NEW YORK.

BASEBALL GLOVE.

Application filed March 16, 1923. Serial No. 625,596.

To all whom it may concern:

Be it known that I, PHILIP KENNEDY, a citizen of the United States, and resident of Gloversville, in the county of Fulton and State of New York, have invented certain new and useful Improvements in Baseball Gloves, of which the following is a specification.

This invention relates generally to improvements in gloves, more particularly to improvements in gloves of the class known as fielders' gloves, and it consists in the combinations, constructions and arrangements herein described and claimed.

An object of the invention is to provide a glove of the character described which is constructed in such manner as to afford relatively great protection to the fingers of a wearer and to hold the fingers against being bent backward and broken by the impact of a ball striking against the palm of the glove.

A further object of the invention is to provide a glove of the character described which has means for staying the finger stall and thumb stall portions thereof to one another and for binding such portions together so that a relatively deep pocket is provided in the palm of the glove and the adjacent finger and thumb stall portions of the glove are held against spreading to an extent sufficient to permit a ball striking the palm of the glove to escape from the glove.

A further object of the invention is to provide a glove of the character described which has the relatively movable portions thereof adjustably connected together in such manner as to yield under the impact of a ball striking the palm of the glove to provide the relatively deep pocket in which the ball will be snared while at the same time the relatively movable portions are stayed to each other and held against distortion and protected against undue strain at the points where the greatest stresses are imposed upon the glove in service, whereby the glove embodying the invention will last longer in the service for which it is intended than a glove of ordinary construction in like service.

Other objects and advantages will be apparent from the following description, considered in conjunction with the accompanying drawings, in which—

Figure 1 is a plan view showing a glove

embodying the invention, the glove being disposed with the back thereof uppermost.

Figure 2 is a section on the line 2—2 of Figure 1,

Figure 3 is a section on the line 3—3 of Figure 1,

Figure 4 is a section on the line 4—4 of Figure 1,

Figure 5 is a plan view of a fourchette comprised in the glove,

Figure 6 is a plan view of one of the back sections comprised in the glove, and

Figure 7 is a perspective view of one of a plurality of attaching elements comprised in the glove.

Referring now to the drawings, a glove formed according to the invention comprises a body indicated generally at 1, the body being provided with finger stall portions 2, 3, 4 and 5, and a thumb stall portion 6. The body 1 comprises an outer cover designated generally at 7, an inner lining 8 and packing 9 arranged between certain portions of the covering 7 and lining 8, as is usual in a glove of the class described. The cover 7 is of novel construction and will be hereinafter described in detail.

The cover 7 comprises a palm 10 formed integrally with the finger fronts 2^a, 3^a, 4^a, 5^a and also with the outer half portion 2^b of the back of the fourth finger and with the lateral marginal portions 11 and 12 respectively of the back of the glove cover. An opening is formed at the juncture of the lateral back section 12 and the palm 10 and from this opening extends a thumb piece 14 which is joined at its base to the adjacent edge portions of the back section 12 and the palm 10. The portions of the cover 7 surrounding the base of the thumb piece 14 are thus formed in one continuous piece which produces a relatively strong construction and at the same time a cover which is adapted to flex or give at the juncture of the thumb piece and palm so that a relatively deep pocket will be formed when a ball strikes the palm of the glove at the juncture of the latter with the thumb piece.

The cover back also includes an outer section 15 of the front or first finger back which is joined along its outer edge for the greater part of the length of the latter to the outer edge of the finger front 5^a as indicated at 16 and is joined along its outer edge

for the remainder of the length of the latter to the forward edge of the back section 12, as indicated at 17. The finger back section 15 is joined at its rear edge to the piping 18 surrounding the usual opening in the glove back, which opening is partially defined by the wrist strap portion 19 of the glove body.

Three fourchettes 20 and a like number 10 of cover back sections 21 are arranged between the inner edges of the finger back sections 2^b and 15, each of the fourchettes being formed to provide a substantially V-shaped notch at its rearward edge receiving 15 a substantially V-shaped projecting front end portion of one of the back sections 21 and being secured to the latter as at 22. Each of the back sections 21 is secured at its rearward edge to the piping 18 and 20 the fourchettes 20 are secured at their inner edges to the finger fronts and at their outer edges to one another or to the finger back sections 2^b and 15, as is usual.

The connected together edge portions of 25 the respective parts of the cover which have been described are preferably joined by welt seaming so that the connected together parts are not likely to rip apart at the seams and a relatively strong cover construction is thus 30 produced.

It of course will be understood that the lining 8 conforms substantially in contour to the cover 7 and may consist of any suitable or desired number of parts secured together by stitching or in any other suitable known manner. The provision of the V-shaped seams or joints between the fourchettes and the back sections insures a glove body which will be extremely flexible at the 35 juncture of the finger stalls with the palm portion of the body, whereby the body will give in a manner adapted to aid in snaring a ball striking the palm of the glove.

In order to reinforce the glove body at 40 points adjacent to the outer ends of the fingers and to stay the finger stalls to each other at points adjacent to their outer ends whereby the impact arising when a ball strikes the palm of the glove will cause 45 spreading of the fingers at their bases and a converging of the fingers at their ends, the invention contemplates the provision of a lace or tie member 23 arranged to connect the respective finger stalls and the thumb stall in series in a manner which 50 will now be described. Attaching strips or ears 24 having eyelets 25 through which the lace 23 may extend are provided, there being one of the attaching strips for each 55 of the finger stalls 2, 3 and 4 and two of the attaching strips for the front or first finger 5. The attaching strips 24 for the finger stalls 2, 3 and 4 are arranged to extend outwardly from the backs of the finger stalls 60 along the longitudinal median lines of the

latter and at points where the outermost joint of the fingers will be disposed. The attaching strips 24 may be secured to the finger stalls 2, 3 and 4 at the seams between adjacent sections of the finger backs 70 as indicated at 26 in Figure 2. One of the attaching strips for the front finger 5 is secured along the longitudinal median line of the latter between the sections of the finger back in the same manner as the attaching strips for the fingers 2, 3 and 4 are secured to the latter. The second attaching strip for the front finger 5 is secured to the latter at the seam between the outer edge of the section 15 of the finger back and the finger front 5^a, that is, at the side of the finger 5 adjacent to the thumb 6. Eyelets 27 and 28 respectively are provided in the thumb piece 14 at opposite sides of the longitudinal seam 29 which joins the lateral edges of the thumb piece to one another, the eyelets 27 and 28 being located 85 adjacent to the outer end of the thumb.

From the foregoing description of the various parts of the device, the operation 90 thereof may be readily understood. The lace 23 is extended through the eyelets of the respective attaching ears 24 in sequence, beginning with the attaching ear carried by the fourth finger and is extended through 95 the eyelets 28 and 27 of the thumb piece. The one end of the lace is held against passage through the eyelet of the attaching ear carried by the fourth finger, as by being provided with a knot 30. The free end portion of the lace is threaded through the eyelets of a desired number of the fingers, beginning with the eyelet on the front or first finger and the portion of the lace extending through the respective eyelets is 100 adjusted in length to adjust the position of the finger stalls and thumb stall in respect to one another, a knot 31 being formed at the inner end of the adjacent eyelet and to thus 105 maintain the desired adjustment of the finger stalls and thumb stall in respect to one another.

When a ball strikes the palm of the glove body at the juncture of the palm and the thumb stall and first finger stall, the base 115 portions of the finger stalls will give or spread somewhat while the outer end portions of the fingers and the thumb will be held against spreading by the lace 23, whereby a relatively deep pocket conforming substantially to the contour of the ball will be formed in the glove body, thus tending to hold the ball in the glove. Moreover, the fingers and the thumb will be stayed to one another, thus precluding the bending back 120 of any one of the fingers or the spreading of adjacent fingers or the forefinger and thumb to an extent sufficient to cause injury to the fingers of the hand of a wearer or to permit the ball to slip between adjacent fingers or 125 130

the forefinger and thumb of the glove. It will be apparent that a glove equipped with the invention will retain its shape for a relatively long time in the service for which it is intended since the relatively movable parts of the glove are effectually stayed to one another and reinforced.

Obviously, the invention is susceptible of embodiment in forms other than that illustrated in the accompanying drawing and I therefore consider as my own all modifications and adaptations of the form of the device herein disclosed which fairly fall within the scope of the appended claims.

Having thus described the invention, what I claim is:—

1. In a glove, a flexible connection extending transversely of the fingers of the glove across the backs of the fingers and adjustably connecting the respective fingers together.
2. In a glove, a lace extending across the backs of the fingers of the glove and connecting the fingers in series and to the thumb of the glove.
3. In a glove, means extending across the backs of the fingers of the glove and adjustably connecting the respective fingers in series and connecting the forefinger to the thumb of the glove.
4. In a glove, means extending across the backs of the fingers of the glove and adjustably connecting the respective fingers in series and connecting the forefinger to the thumb of the glove, the points of connection of said means with the respective fingers and with the thumb of the glove being relatively adjacent to the outer ends of said fingers and thumb.
5. In a glove, means extending across the backs of the fingers of the glove and adjustably connecting the respective fingers in series and connecting the forefinger to the thumb of the glove, the points of connection of said means with the respective fingers and thumb being at the backs of the fingers and at the inner side of the thumb.
6. In a glove, means extending across the backs of the fingers of the glove and adjustably connecting the respective fingers in

series and connecting the forefinger to the thumb of the glove, the points of connection of said means with the respective fingers and thumb being at the backs of the fingers and at the inner side of the thumb, and at points relatively adjacent to the outer ends of the fingers and thumb.

7. In a glove, attaching ears extending rearwardly of the backs of the respective fingers of the glove and substantially in a line extending transversely of the glove adjacent to the tips of the fingers, said ears being provided with alined eyelets, and the thumb of the glove being provided with a plurality of eyelets in its inner side and adjacent to the outer end thereof, and a lace threaded through the eyelets on the fingers and the eyelets of the thumb in sequence, beginning with the eyelet on the fourth finger, and then being re-threaded through certain of the eyelets on the fingers beginning with the eyelet on the finger proximate to the thumb, as and for the purpose described.

8. In a glove, a cover including a palm integral with finger fronts and with the lateral marginal portions of the cover back and the lateral marginal section of the back of the fourth finger, said palm and one of said lateral marginal portions of the cover back being formed with a thumb opening at their juncture with each other and being continuous about said thumb opening, an outer longitudinal section of the back of the first finger secured along its outer edge to the corresponding edge of the front of the first finger and being secured adjacent to its rearward end to said one lateral marginal portion of the back; fourchettes arranged between the inner edges of the outer sections of the first and fourth fingers and being secured at their inner edges to the finger fronts, and back sections at the rear of the fourchettes and being secured at their front edges to the rear edges of the latter, the meeting edges of each fourchette and the back section at the rear thereof being complementary in respect to each other and each being substantially V-shaped in outline.

PHILIP KENNEDY.
